UNITED STATES PATENT OFFICE.

JOHN PELZER, OF ORANGE, NEW JERSEY.

DEVICE FOR OPENING AND CLOSING TRANSOMS OR WINDOWS.

1,156,020.

Specification of Letters Patent.

Patented Oct. 5, 1915.

Application filed August 14, 1913. Serial No. 784,700.

To all whom it may concern:

Be it known that I, JOHN PELZER, a citizen of the United States, and resident of Orange, county of Essex, and State of New Jersey, have made a new and useful Invention in Devices for Opening and Closing Transoms or Windows, of which the following is a specification.

My invention is directed particularly to novel mechanism for controlling the opening and closing of transoms or windows which are not usually easy of access, and has for its objects—First, to devise such mechanism as will be simple, cheap and efficient and can be wholly concealed in the facing of a door or in the walls of a building. Second, to devise mechanism for such purpose as will render it possible to effect the accurate closure of the transom at all times. Third, to devise such mechanism as will make it easily accessible at all times and will not be liable to get out of repair or become inoperative at any time, as is so often the case with transoms made operative at a point accessible to the user, and will also make it possible to easily, quickly and completely remove the transom for the purpose of cleaning, repairing, etc.

My invention will be fully understood by referring to the accompanying drawings, in which,

Figure 1 is a part sectional, part side elevational view of the control mechanism proper and its attachment to the transom. Fig. 2 is an elevational view of the lower portion of Fig. 1, as seen looking from right to left, the same being broken away at the interior for the purpose of showing the operation thereof. Fig. 3 is an enlarged detail view of the connections between the operating part of the mechanism and the transom proper. Fig. 4 is a perspective view of the upper portion of a door showing a transom with my improved mechanism attached thereto, broken sections being shown for more clearly illustrating the details of the mechanism. Fig. 5 is a side elevational view of one of the attachments which detachably connect both sides of the transom to its window. Fig. 6 is a similar view of one of the attachments which connect the opposite sides of the transom to the journal bearings in the door facing, the pivot at the right hand end being broken away below. Fig. 7 is a plan view of the parts shown in Figs.

5 and 6 when connected together in the manner shown in Figs. 1 and 4.

Referring now to the drawings in detail, 1 represents a metal face plate for supporting the operative parts of the transom moving or operating mechanism, and 2, 2, are two metal supporting plates for the rack cast integral with the metal face plate 1 at right angles thereto and curved outwardly at their middle, as shown.

3 is a rectangularly shaped guide-bar for the mechanism secured to the supporting plates 2 by screws 4, 4, at its opposite ends.

5 represents a plate adapted to slide upon the guide-bar 3 and having an outwardly extended side 6 provided with an opening for receiving a propelling pin *p*.

7 is a sliding rack secured to, or integral with if preferred, the bottom of the E-shaped plate 5 and provided with a plurality of operating teeth 8.

9 represents a short rectangular shaped bar or head which is secured on the end of a rotatable shaft 11 journaled in a journal bearing 12 integral with the face plate 1, 80 said head 9 being provided with two propelling pins or teeth 10 adapted to mesh with the teeth 8 of the rack 7. The rotatable shaft 11 is located at right angles to the bottom of the E-shaped plate 5 and consequently at an angle to the rack 7 and the teeth 8, this angle being preferably 90°. These two propelling pins or teeth 10 and head 9 constitute in effect a pinion adapted to move the rack 7 upward or downward 90 when continuously rotated in either direction.

8 represents a leaf-spring secured at one end by rivets to the inner side of one of the supporting plates 2 (see Figs. 1 and 2) and bearing at its free end against the flat surfaces of the head 9 when the same is rotated, this spring being adapted to positively force the head 9 so that the teeth 10 are located in a vertical or locking position 100 at each half revolution.

13 is an operating knob secured to the end of the shaft 11 and 14 represents a connecting link or rod, 15 being a short connecting lever having an enlarged end for connecting 105 it to the pivots of the transom.

The parts so far described, except the flat locking spring 8, are disclosed in a copending application filed by me in the U. S. Patent Office on the 5th day of November, 1912, 110

and bearing Serial No. 729,663, and directed to an improvement in mechanical movements, and their operation will be understood.

5 Referring now to Figs. 1, and 3 to 7 inclusive, I will describe the entire invention, as follows—

16 is an enlarged end of the lever 15 for a purpose to be hereinafter described.

10 17 represents the transom pivotally held by my improved means in the upper portion of the door facing 18, see Fig. 4.

15 19, 19 represent two journal bearings secured to the opposite inner faces of the door by screws 20, 20. 21, 21 are journals or pivots sustained by the journal bearings 19, 19. The journal 21, seen in Figs. 1 and 3 and on the right in Fig. 4, differs from the other journal 21 on the left in that it is provided with means for effecting the angular 20 adjustments of the transom, so that after it is put together it may be adjusted so as to accurately fit the opening in the frame in a vertical position when closed, and to accomplish this I provide said journal with two 25 oppositely disposed grooves 22, 22 (see Figs. 3 and 4) and arrange the journal itself to accurately fit the enlarged end 16 as shown in Fig. 1, and I provide a key 23 with upper turned ends (see Fig. 3) and the enlarged end 16 with two adjusting screws 24, 24, adapted to bear at their inner ends against the key 23 so that the angular position may be effected by the adjustment of these 30 screws and the transom locked by the action of the teeth or pins 10, 10, said pins being in vertical alinement when the transom is closed, as will be described later on.

25, 25 represent a pair of narrow sustaining plates each permanently secured by two 40 screws 28, 28 in grooves *g* to the opposite ends of the transom, as shown in enlarged view Fig. 3. Each of these plates is forked at its upper end, as shown in Fig. 5, for the 45 purpose of acting as a journal bearing for the journals 21 and turned outward in opposite directions at its lower end, as shown by the numerals 26, Figs. 3, 5 and 7.

29, 29 are narrow sustaining plates similar 50 to the plates 25 and secured thereto by screws 32 and provided at their lower ends with downward projections 30 adapted, when in position, to be vertically detachable from the outwardly turned lower ends of the 55 plates 25, said outwardly turned ends acting as shoulders. These plates 29 are integrally connected at their upper ends to the journals 21 and are, therefore, adapted to adjust the transom angularly with relation to the 60 journal bearings.

31, 31 are screws provided with heads as shown and detachable from the inner ends of the journals 21.

65 The parts of my improved mechanism are assembled as follows—The metal face plate

1 is secured by screws to the inner casing of the door and in the manner shown in Fig. 4. The controlling pin *p* is then inserted in the extended side 6 and the vertical connecting link or rod 14 which is connected in turn to the short connecting lever 15. The flat journal bearings 19 are then secured by the screws 20 in the inner faces of the door. The sustaining plates 25 are secured in the manner shown with their forked ends extending upward in the groove *g* within the opposite ends of the transom by screws 28, as shown, the lower downward projections 30 having a bearing between the outwardly turned ends 26 of the plates 25. The short 70 connecting lever 15 is connected to the journal 21, the key 23 having first been inserted, after which the transom is turned to proper position and adjustment effected by the screws 24, 24 by adjusting them against the 75 key 23 and the faces of one of the grooves 22. The device is now ready for operation and any turn of the knob 13 in a given direction either opens or closes the transom a proportionate amount, each semi-turn 80 placing the teeth 10 of the head 9 in the position shown in Fig. 2 by reason of the action of the strong flat spring *s*, thereby effectually locking it. It will thus be seen that with this mechanism the transom may 85 always be operated in a given direction and that after the semi-revolution of the knob 13 it assumes a definite locked position and that adjustment thereof may be effected by varying the position of the adjusting screws 24 90 with relation to the key 23.

It will also be understood that the transom may be readily removed for the purpose of cleaning, or for inserting a new glass, if the same be broken, or for the purpose of 95 painting the frame thereof; or for repairs generally.

I do not limit my invention to the specific structural device herein shown and described as I believe it is broadly new with 100 me to provide a transom which automatically assumes a self-locking position for every portion of its movement. I believe it is also broadly new with me to provide a transom operating mechanism which permits of the ready removal of the transom without materially disturbing the operative parts thereof and my claims are generic in these particulars.

I make no claim in the present application 105 to a mechanical movement acting upon the principle disclosed in the mechanism herein described, such mechanical movement being described and claimed in a copending application above referred to and bearing Serial No. 729,663.

Having thus described my invention what I claim and desire to secure by Letters Patent of the United States is—

1. A transom operating device embracing 110

rack and pinion mechanism for giving to the transom motion in opposite directions, and simultaneously automatically locking it twice in each revolution of the pinion in any position as it is advanced; in combination with means for adjusting the angular position of the transom.

2. A transom operating device embracing rack and pinion mechanism for giving to it motion in opposite directions, the transom being detachably journaled in the window

of a door and provided with adjusting screws connected with one of the pivots and the operating mechanism for varying its angular position.

In testimony whereof I have signed my name to this specification in the presence of two subscribing witnesses.

JOHN PELZER.
